UNITED STATES PATENT OFFICE.

HENRY H. CHRISTMAN, OF READING, PENNSYLVANIA.

DESIGN FOR AN AGITATOR-STANDARD FOR WASHING-MACHINES.

49,175.

Specification for Design.

Patented June 13, 1916.

Application filed April 4, 1916. Serial No. 88,952. Term of patent 7 years.

To all whom it may concern:

Be it known that I, HENRY H. CHRISTMAN, a citizen of the United States of America, residing at Reading, in the county of Berks and State of Pennsylvania, have invented a new, original, and ornamental Design for an Agitator-Standard for Washing-Machines, of which the following is a specification, reference being had to the accompanying drawing, forming a part thereof.

In the drawing:—Figure 1 is a side elevation of an agitator standard illustrating my new design. Fig. 2 is a plan view thereof.

I claim:—

The ornamental design for an agitator standard for washing machines, as shown.

HENRY H. CHRISTMAN.
